C. L. GOODRUM

TELEPHONE SYSTEM

Filed Dec. 2, 1920

Inventor:
Charles L. Goodrum.
' E.R. Nowlan Atty.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed December 2, 1920. Serial No. 427,827.

To all whom it may concern:

Be it known that I, CHARLES L. GOODRUM, a citizen of the United States, residing at New York, in the county of New York, 5 State of New York, have invented certain new and useful Improvements in Telephone Systems, of which the following is a full, clear, concise, and exact description.

This invention relates to telephone systems, and more particularly to such systems adapted for paging or dictating purposes.

An object of the invention is to provide improved and simplified means whereby any one of a plurality of calling stations 15 may selectively call any one of a plurality of loud speaking stations. By the term loud speaking stations is meant a station equipped with a loud speaking receiver and a transmitter.

20 To attain the above mentioned object the invention contemplates extending each of the calling, and each of the loud speaking stations over three conductors to a central point, at which point automatic switches controlled from calling stations are provided for extending a connection from a calling station to a loud speaking station. Each calling station may be provided with an impulse sender for directly setting 25 numerical switches, and an ordinary transmitter and receiver of any well known and approved type. When a connection is extended from a calling station to an idle loud speaking station conversation may proceed 30 immediately, no call bell being provided at the called station. The called station responds by simply speaking into the transmitter. The loud speaking receiver thus serves as a calling signal. Two talking 35 circuits including three talking conductors are provided between a calling and called subscriber, each talking circuit including a transmitter and a receiver. If the called line is busy, a busy tone is automatically 40 connected to the called line for indicating the busy condition to the calling subscriber. The simple restoration of the receiver to the switch hook at the calling station releases 45 the established connection.

50 Referring to the accompanying drawing which illustrates one embodiment of the invention there is shown a calling substation O connected by means of three conductors to a non-numerical switch F at a central office. Accessible to the non-numerical

switch F is a connector switch C which is adapted to be directly set under the control of the impulse sender S at the calling station O. At L there is shown a loud speaking station comprising a transmitter and a 60 loud speaking receiver. The transmitter and loud speaking receiver may be of types well known in the art.

With this description of the elements, it is thought that the invention will be more 65 fully understood by reference to the following detailed description of the operation.

A party at station O, desiring to talk to a person who may be in the vicinity of a 70 loud speaking station L, removes the receiver from the switch hook 2 whereupon line relay 14, individual to the station O, is energized and causes the operation of the non-numerical switch F thereby extending the line of station O to an idle connector 75 switch C. The non-numerical switch F may be a line finder such as shown in my Patent No. 1,193,137 issued August 1, 1916. Referring to Fig. 1 of said patent the terminal 132, brush 133 and conductor 134 80 correspond to terminal 9, brush 13 and conductor 80, respectively. Release conductor 123 of said patent corresponds to release conductor 81 of the present application. To adapt the finder of the said patent to the 85 system of the present invention, it is necessary to add the terminal 8 and brush 12 to provide for the additional lowermost talking conductor 82. As soon as the calling line is extended through to the connector C, 90 cutoff relay 15 operates and disconnects the line relay 14 as described in detail in said patent. Line relay 20 of the connector switch C is energized when the finder connects with the calling line over a path extending from grounded battery, left hand winding of relay 20, brush 12 and terminal 8 of switch F, transmitter 4, receiver hook 2 and contact 3 thereof, impulse sender S, terminal 7, brush 11, side switch arm 51 in 95 its first position and right hand winding of relay 20 to ground. Relay 20, in operating, completes an obvious circuit for slow-to-release relay 21.

The party at station O may now operate 100 the sender S for the purpose of setting the selector switch C upon the terminals of the desired station L. It will be assumed that the number of the desired station is 24. The party at station O will first dial the 110

digit 2 thereby causing two interruptions of the circuit of relay 20. In response to the first interruption of the circuit, relay 22 will be operated over a path extending from 5 ground, armature and back contact of relay 20, right hand armature and front contact of relay 21 and winding of relay 22 to grounded battery. Relay 22, in operating, completes an obvious circuit for slow-to-release relay 24. Relay 24, in operating, completes an obvious circuit for escape magnet 25. Relays 21, 22, and 24 are preferably of the slow-to-release type so as to maintain their armatures attracted during the transmission of the impulses of a series.

In response to each interruption of the circuit of line relay 20, primary magnet 23 is energized over a path extending from ground, armature and back contact of relay 20, right hand armature and front contact of relay 21, side switch arm 53 and its first contact and winding of primary magnet 23 to grounded battery. In response to the two impulses transmitted to the primary 25 magnet 23, the brushes 40 to 43 inclusive of connector switch C will be moved two steps in their primary movement.

As soon as the last impulse of the tens series has been transmitted to the line relay 30 20, the circuit for relay 20 will be closed for a relatively long interval thereby interrupting the circuit for, and causing the release of, slow-to-release relay 22. Relay 22 in retracting its right hand armature releases slow-to-release relay 24 which in turn 35 opens the circuit for escape magnet 25. Escape magnet 25 is designed so as to move the side switch arms 50 to 53 inclusive of the connector switch C one step upon its de- 40 energization so that said side switch arms are moved into their second positions.

The operator now dials the digit 4 thereby causing four interruptions of the line 45 circuit. The line relay 20 thereupon retracts its armature four times. Upon the first retraction in response to this series of impulses, slow-to-release relays 22 and 24 and escape magnet 25 are, in turn, successively energized. The secondary magnet 26 50 will be energized each time relay 20 retracts its armature over a path extending from ground, armature and back contact of relay 20, right hand armature and front contact of relay 21, side switch arm 53 and its sec- 55 ond contact, winding of magnet 26 to grounded battery. The brushes 40 to 43 inclusive are thereupon brought to rest upon the terminals 44 to 47 inclusive of the station L.

60 As soon as the last impulse of the units series of impulses has been delivered to the relay 20, the circuit of relay 20 will remain closed thereby causing the release of slow-to-release relays 22 and 24 and in turn 65 escape magnet 25. Escape magnet 25, in de-

energizing, moves brushes 50 to 53 inclusive from their second to their third positions.

The party at the calling station may now talk over the established connection and if the called party is within hearing distance 70 of the loud speaking receiver 49, he may respond, without actuating any mechanism at his station, by talking into the transmitter 48 thereby notifying the calling station of his presence. The transmitter 48 is prefer- 75 ably of the sensitive type in order that the called party may actuate it by speaking from a distance, if desired. Talking battery for the calling station is supplied through the left hand winding of relay 20, 80 brush 12, and terminal 8 of switch F, transmitter 4, receiver switch hook 2 and contact 3 thereof, impulse sender S, terminal 7 and brush 11, side switch arm 51 and its third contact, brush 41 and terminal 45 of connector switch C, receiver 49, terminal 46, brush 42, third contact of side switch arm 52 and side switch arm 52, through the right hand winding of relay 20 to ground. In providing condenser 61 in one of the talking 85 conductors, a series circuit for direct current is provided through the calling transmitter and the called receiver and a circuit for operating the impulse relay 20 to control the movement of the switch is also provided.

The called subscriber's transmitter is supplied with talking battery over a path extending from negative pole of battery B, side switch arm 50 and its third contact, brush 40 and terminal 44 of switch C, transmitter 48, terminal 45 and brush 41, third contact of side switch arm 51, and the right hand winding of induction coil 60 to positive pole of battery B. Although various batteries including the battery B are shown on the drawing it will be understood that they have been shown only to simplify the drawing and that a common central battery is used. The called subscriber in responding affects the transmitter thereby setting up currents in the primary winding of induction coil 60 which are induced into the secondary of said coil and traverse brushes 10 and 11 and terminals 6 and 7 of switch F and the receiver 1.

110 At the conclusion of the conversation, the calling subscriber restores the receiver 1 to the switch hook 2 thereby opening the circuit for line relay 20. Relay 20, in de- 115 energizing, releases relay 21 and causes the completion of a circuit for release magnet 29 over a path extending from grounded battery, winding of magnet 29, off normal contact 30 of switch C, back contact and right hand armature of relay 21 and back contact and armature of relay 20 to ground. Magnet 29, in operating, locks through its own contacts and causes the release of the switch C in the manner well known in the art. Relay 21 in retracting its left armature 120

causes the release of the line finder F, which switch opens the circuit of cut-off relay 15, as described in detail in said patent. As soon as the connector switch C returns to normal, the locking circuit for release magnet 29 is opened.

If the called line had been busy, ground potential would have been present upon terminal 47 of the called station and before 10 the relay 24 would have deenergized, relay 27 would have operated and would have connected busy tone to the calling party at station C for the purpose of informing him of the busy condition of the called station. 15 The path for the energization of relay 27 may be traced as follows: grounded battery winding of relay 27, front contact and left hand armature of relay 24, back contact and left hand armature of relay 22, brush 43 and 20 terminal 47 of switch C to ground. Relay 27, in operating, locks through its inner right hand contact to ground at the front contact and left hand armature of relay 21. The path for the busy tone from the source 28, 25 extends through the left hand armature and front contact of relay 27, and through condenser 31 to the calling line. As soon as the relay 27 operates, release magnet 29 operates over a path extending from grounded 30 battery, winding of magnet 29, contacts 30, and outer right hand armature and front contact of relay 27 to ground. Magnet 29 in operating locks and causes the return of the switch C to normal. Relay 27 remains 35 operated until the calling subscriber hangs up and releases relays 20 and 21. The releasing operations takes place upon the restoration of the receiver as described in connection with a successful call.

40 What is claimed is:

1. In a telephone system, a telephone station having an ordinary transmitter and a receiver, an impulse sender thereat, a tele-

phone station comprising a loud speaking receiver and a sensitive transmitter, and 45 means including an automatic switch adapted to be set under the control of said sender for simultaneously establishing a plurality of conversational circuits between said stations, said circuits each including a transmitter and a receiver. 50

2. In a telephone system, a calling telephone station, an impulse sender thereat, a called station including a loud speaking receiver and a sensitive transmitter, and means 55 including an automatic switch for establishing a pair of conversational circuits between said stations, said circuits each including a transmitter and a receiver.

3. In a telephone system, a calling station 60 comprising a transmitter and receiver, a plurality of stations, each comprising a loud speaking receiver and a sensitive transmitter, an automatic switch, and an impulse sender at the calling station for controlling 65 said switch to connect the calling station with another station, said connection including a pair of talking circuits one of said talking circuits including the receiver and the sensitive transmitter and the other of 70 said circuits including the transmitter and the loud speaking receiver.

4. In a telephone system, a plurality of calling stations, called stations, three conductors extending from each of said stations 75 to a central point, automatic switches at said central point for said conductors, a circuit for setting said automatic switches including two of said three conductors in series to establish a pair of conversational circuits between the calling and called stations formed by said three conductors. 80

In witness whereof, I hereunto subscribe my name this 23rd day of November A. D., 1920.

CHARLES L. GOODRUM.
